US00D791755S

(12) **United States Design Patent** (10) **Patent No.:** **US D791,755 S**
(45) **Date of Patent:** **** Jul. 11, 2017**

(54) **CASE FOR ELECTRONIC DEVICE**

(71) Applicant: **Dae-Young Kim**, Seoul (KR)

(72) Inventor: **Dae-Young Kim**, Seoul (KR)

(73) Assignee: **SPIGEN KOREA CO., LTD.**,
Geumcheon-Gu, Seoul (KR)

(**) Term: **14 Years**

(21) Appl. No.: **29/506,117**

(22) Filed: **Oct. 13, 2014**

(51) LOC (10) Cl. **14-01**

(52) U.S. Cl.

USPC **D14/250**

(57) **CLAIM**

The ornamental design for a case for electronic device, as shown and described.

DESCRIPTION

FIG. 1 is a front perspective view of a case for electronic device, comprised of inner shell and outer frame, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded front perspective view thereof showing the inner shell and outer frame of the case for electronic device separated for clarity of disclosure;

FIG. 10 is an exploded rear perspective view thereof;

FIG. 11 is a front perspective view showing only the inner shell for clarity of disclosure;

FIG. 12 is a rear perspective view thereof;

FIG. 13 is a front perspective view showing only the outer frame for clarity of disclosure; and,

FIG. 14 is a rear perspective view thereof.

1 Claim, 14 Drawing Sheets
